ADJUSTABLE FLOWER STAND.

No. 375,519.

Patented Dec. 27, 1887.

UNITED STATES PATENT OFFICE.

ZECHARIAH WALKER, OF TRENTON, NEW JERSEY.

ADJUSTABLE FLOWER-STAND.

SPECIFICATION forming part of Letters Patent No. 375,519, dated December 27, 1887.

Application filed July 29, 1887. Serial No. 245,605. (No model.)

To all whom it may concern:

Be it known that I, ZECHARIAH WALKER, a citizen of the United States, residing at Trenton, in the county of Mercer and State of New Jersey, have invented certain new and useful Improvements in Adjustable Flower-Stands; and I do declare the following to be a full, clear, and exact description of the invention, such as will enable others skilled in the art to 10 which it appertains to make and use the same.

This invention relates to certain improvements in that class of flower-stands which are employed to support growing flowers and plants within the windows of dwellings and 15 other buildings; and it has for its objects to provide a stand that may be accommodated to any window vertically, horizontally, and longitudinally, and by which the flowers or growing plants may be exposed to sunlight, air, or 20 rain when convenient, at the expense of little labor, as more fully hereinafter set forth. These objects I attain by the means illustrated in the accompanying drawings, in which—

Figure 1 is an end elevation of my invention, 25 showing the stand and its attachments complete. Fig. 2 is a vertical transverse section of the stand and shelf-frame, showing the same in connection with an ordinary window. Fig. 3 is a detached perspective view of an adjustable connection, by means of which the table or stand is secured to the sill of a window. Fig. 4 is a detached side elevation of a device for locking the outside window-blinds when 30 opened and for supporting the sustaining- 35 rails of the shelf-frame of the device when extended. Fig. 5 is a rear view of the shelf-frame stand and shelf-frame thereon, showing the means by which they are adjusted to adapt them to windows of different sizes and heights. Fig. 6 is a transverse vertical sectional view 40 taken on the line $x-x$, Fig. 1. Fig. 7 is a top view of the table or stand with the other parts removed therefrom. Fig. 8 is a bottom plan view of the shelf-carrying frame. Fig. 9 is a 45 detached view of the frame upon which the shelf-frame rides. Fig. 10 is a detached view in perspective of one of the adjustable shelves; and Fig. 11 is a detached view of an adjustable 50 splash-plate to be secured within the window at the sill of the same to prevent slopping in

watering the flowers or plants, as more fully hereinafter set forth.

Referring to the drawings, A is a shelf-frame; A', a bed or table, which is supported upon vertical standards or legs B near each 55 corner. The said legs or standards are provided with lateral horizontal extensions C, which are provided with screw-threaded apertures, through which work vertically the screw-threaded posts or standards D, which at 60 their lower ends are bifurcated and provided with casters E, whereby the bed or table may be adjusted so as to be level with the lower sill of a window of any elevation. The said extensions and the bed or table are braced by 65 means of the panels or connecting-sections F, which are secured to the said bed or table and extensions by means of the screws G. The bed or table has extending around its edge on its upper surface a flange, a , and at the front 70 and rear, near each end, it is provided with a longitudinal slot, H, for the purpose herein-after explained.

I are two transversely-arranged guides or ways, which are supported by footed standards I', which are adjustably secured to the table or bed by means of set-screws L, passing through the slots above mentioned, so that said guides or ways may be adjusted to the width of any window, for the purpose more 80 fully hereinafter set forth. Within the guides or ways are telescoping sections M W, forming a track, the guides or ways I being formed with side guides, P, in which the side wings, R, of the sections M are adapted to slide, and 85 with upright flanges S, between which travel the flanged wheels T of the shelf-frame before mentioned. The said sections M are beveled on their upper edges and form the track for the wheels T. Within the sections M, and ar- 90 ranged to slide back and forth therein, are ar- 95 ranged the flat sections W, before mentioned, the upper edges of which extend above the beveled edges of said sections M and form a continuation of the same when extended, so as to support the wheels of the shelf-frame and permit the same to be run outside clear of the window-frame, so as to expose the flowers to the action of air and sunlight when desired. The inner section, W, of the guide or track is 100

provided with a slot, X, into which passes a pin, V, secured to the flange of the outer fixed section, so as to form a stop for the said inner section when drawn out. The downwardly-
5 turned flanges of the outer or main mixed section are also provided with screw-threaded apertures Z, through which stop pins or screws V' may be passed. The said screws pass through the slot X in the longitudinally-adjustable sections W, so as to stop the said sections in their inward movements. The longitudinally-moving sections W at their outer ends are provided with upturned stops B', which confine the shelf-frame to the track when
15 moved forward.

The shelf-frame has an open front, and is composed of the lateral sections A² A², which have rectangular rear vertical walls, A³, slotted horizontally, as shown at C³. These rear slotted walls are connected by means of a rear vertical wall, A⁴, carrying set-screws D', adapted to pass through the slots C³, whereby the said frame may be made adjustable for windows of different widths. The lateral ver-
25 tical walls A² of this shelf are provided on their inner sides with horizontally-fixed edges or supports Z', designed to sustain the shelves which receive the flower-pots.

There are flanged rollers, which are journaled 30 on the bottoms of the lateral sections of the shelf-frame, and which wheels travel on the track before mentioned, secured to the bed or table of the stand. The side walls of this frame are provided on their inner sides with 35 horizontal strips or ledges Z', to support the shelves S'. The bed or table is provided with a series of apertures, E', in line with the slots H, before mentioned, and which are adapted to receive the end of a pin, F', secured adjust-
40 ably to a slotted link, G', which has a downwardly-bent end, H', adapted to be secured in a slot in the bracket R', secured to the sill of the window. The pin F' is provided with a seat, K, and a bolt, I', passing therethrough and through a slot in the link G', whereby the pin F' is made adjustable, but may be clamped in place by a nut, i.

P indicates a plate which is pivoted to the outside of the frame above the sill, and is de-
50 signed to turn down horizontally across the plane of the window when the blinds have been opened. It will thus be seen that this plate will serve to keep the blind from closing when the former has been turned down, as
55 more fully shown in Fig. 4, when it has a rest or bearing in a plate, B', which is also secured to the window-frame exterior to the plate P'. This pivoted arm or plate P' is also notched on its upper edge, as shown at R³, to receive and sustain the track for the shelf-frame when
60 the former has been extended, as more fully shown in Fig. 2 of the drawings.

R² indicates an adjustable splash-board consisting of three sliding sections guided by
65 flanges thereon, and have notches Y in their

lower edges, whereby they may be secured inside of the window over the rails to prevent the slopping of water inside when watering the plants.

S' indicates a series of adjustable sliding shelves, which are composed of two or more flanged sections, and may be adjusted to the shelf-frame as the same is adjusted to windows of different widths.

It will be seen that as constructed my improved stand is adapted to a window of any width or height, and may be so connected in relation thereto that the shelf-frame may be run outside to any desired extent, so as to expose the flowers to the sunlight, air, and rain, so or brought in and protected at night or during stormy weather without unnecessary handling or labor, and also that when brought in the stand may be swung around on the adjustable link, (shown in Fig. 3,) so as to set 85 against the wall at either side of the window, out of the way of the same.

Having described my invention, what I claim is—

1. The combination, with the table having a slot near each corner, of the adjustable stand-
ards provided with apertures, screws passing through said slots and apertures, longitudinally-extensible track-sections supported by said standards, and the shelf-frame provided with flanged wheels adapted to run thereon, whereby the frame may be run in and out of the window to expose or protect the flowers or plants, substantially as specified.

2. The combination, with the bed or table, the adjustable footed standards, and the guides or ways attached to said standards, of the ex-
tensible track constructed in two sections, adapted to slide one within the other and within the guides or ways, and the set-screws 105 whereby said sections are locked in adjusted positions, substantially as set forth.

3. The combination, with the inner track-
sections and the outer section having in-
turned downward extensions, of the brackets 110 secured to the outer sides of the window-
frames, forming seats for the same, whereby the said inner track-sections are held at their outer ends, so as to support the shelf-frame when run out, substantially as specified.

4. The combination, with the frame having the recessed brackets and the movable table having apertures therein, of the hinged link having an adjustable pin adapted to enter said apertures in the table, and provided with a downwardly-bent end adapted to enter the recess in the bracket, whereby the table may be retained in position, and at the same time be permitted to be swung back against the wall out of the way, substantially as specified. 125

5. The combination, with the window-frame, the movable table or bed, the extensible track-
sections, and shelf-frame having flanged wheels adapted to run thereon, of the recessed plates pivoted to the window-frame and adapted to 130

support the extensible track-sections and hold the blinds or shutters open, substantially as specified.

6. The combination, with the table or bed and the adjustably-mounted guides or track-sections, of the adjustable shelf-frame and adjustable shelves, the whole so arranged as to be applied to windows of different widths, substantially as specified.

In testimony whereof I affix my signature in presence of two witnesses.

ZECHARIAH WALKER.
